(74) Attorney, Agent, or Firm — Banner & Witcoff, Ltd.

(57) **CLAIM**

The ornamental design for a shoe, as shown and described.

DESCRIPTION

FIG. 1 is a side photographic view of a shoe showing my new design; and,

FIG. 2 is a front perspective photographic view thereof. The broken lines immediately adjacent to the photographic area represent the bounds of the claimed design and form no part thereof. The remainder of the shoe shown in a greyed out photographic depiction forms no part of the claimed design.
